UNITED STATES PATENT OFFICE.

ANTON JOCH, OF CLEVELAND, OHIO, ASSIGNOR TO THE OHIO BLOWER COMPANY, OF CLEVELAND, OHIO, A CORPORATION OF OHIO.

VENTILATOR.

1,062,012.

Specification of Letters Patent. Patented May 20, 1913.

Application filed September 10, 1910. Serial No. 581,352.

To all whom it may concern:

Be it known that I, ANTON JOCH, a citizen of the United States, residing at Cleveland, in the county of Cuyahoga and State 5 of Ohio, have invented a certain new and useful Improvement in Ventilators, of which the following is a full, clear, and exact description, reference being had to the accompanying drawings.

10 This invention relates to ventilators and has for its object the provision of a device of this character adapted to be located upon the roof of a building and which can be moved by the wind into the position which is 15 most advantageous for its proper operation, and at the same time be opened or closed from below, the opening and closing means being so disposed as not to interfere with its automatic orientation.

20 Further objects and advantages of this invention will appear from the following description and claims.

One embodiment of the invention is illustrated in the accompanying drawing in 25 which—

Figure 1 is a vertical central section of the device, the operating means being shown in elevation; Fig. 2 is a cross section taken on the line 2—2 of Fig. 1; Fig. 3 is a cross sectional view of the operating means and the upper bearing; Figs. 4, 5 and 6 are cross sectional views of details, the same being taken upon the corresponding lines in Fig. 3.

Referring more particularly to the drawing by reference characters, the device consists of a stationary part A adapted to be attached to a roof or pipe end, and a cowl B axially supported upon the part A and adapted to swivel thereupon. The part A 30 is of cylindrical shape and may be formed of a sheet metal band 1 having a base flange 2 for attachment purposes. At a point midway of its length this part carries a spider 3 suitably attached thereto, as by rivets or 35 bolts 4 passing through the sheet metal and through an exterior reinforcing band 5. Rigidly attached at the central point of this spider in any suitable manner, as by clamp nuts 6 and 7, is the upwardly extending tubular support 8, preferably braced in 40 position by brackets 9 as illustrated. The cowl B also comprises a sheet metal casing 10 bent into substantially cylindrical form, but having one side cut away and extended 45 to form the laterally opening window 11, the

sides of the window opening meeting the casing tangentially and being integral therewith. The top and bottom of the extended window portion are closed by plates 13 and 14 suitably connected to the casing 10. Near 50 its upper portion the casing 10 is crossed by braces 15 and 16, which braces are provided at their center point with a cup-shaped bearing 17 adapted to receive the conical end of a stud 18 suitably attached to the top of the 55 support 8 and to support the cowl centrally over the lower part and to allow it to revolve. The lower portion of the casing 10 is made cylindrical, as at 19, and surrounds the upper end of part A with a slight clearance. 60 The casing 10 is also provided with a second spider having legs 20 and 20^a at a point between its ends, said spider being apertured at its center to surround the support 8 and prevent swaying. A collar 21 attached to 65 the support 8 prevents removal of the casing. The upper end of the casing is closed by means of a glass plate 22 seated on an out-turned flange 23 and held in place by bending the edge of this flange up and over 70 its edge, as at 24. I do not wish to confine myself to the use of a glass plate but consider a plate or cap of metal, whether of flat, rounded, or conical form as being within 75 my invention. The edges of the flange 23 may conveniently be serrated to facilitate the attachment of the cover plate. The top plate 13 of the window portion carries a vertical vane 25 adapted to keep the cowl properly directed with regard to the wind in a 80 well known manner, while a counter weight 43 attached to the opposite side of the casing balances the weight of the window, vane and louvers.

For the purpose of regulating the draft 85 through the ventilator, I provide the window with a vertical series of horizontally pivoted louvers 26 connected together by means of a bar 27 so as to be moved simultaneously. The upper louver is provided 90 on its outer face with a bracket 28 to which is pivoted a lever 29 which latter is projected through a slot in the louver just above its axis and extends into the interior of the casing, as shown more particularly in Fig. 2. It will readily be seen that if the inner 95 end of this lever be depressed the louvers will be opened, but the difficulty is to draw and hold this in its depressed position without impeding the free rotation of the cowl. 100 105 110

To effect this result, I attach a bracket 30 to the upper casing at a point diametrically opposite the lever 29 and to this bracket I pivot the end of a bar 31, the other end of which is pivotally connected to the lever 29. At its central part this bar is split and spread so as to surround the support 8, as shown in Figs. 2 and 6, both the branches being perforated at 32 to receive trunnions 33 carried by a sleeve 34 slidably and rotatably mounted upon the support 8. This sleeve is provided at its lower end with a plurality of down-turned hooks 35 which coöperate in supporting a cup-shaped ring 36 which surrounds a second sleeve 37 slidably mounted on the support 8. The upper end of this sleeve is flanged outwardly as at 38, and between this flange and the ring 36 anti-friction balls 39 are placed.

The support 8 has in its side a vertical slot 40 through which a bracket 41 projects, the outer end of this bracket being attached to the sleeve 37 and the inner end to a depending cord or chain 42.

In operation, if the cord 42 be pulled from below, the sleeve 37 is drawn downwardly and carries with it the sleeve 34. This serves to depress the bar 31 and open the louvers 26. At the same time the free rotation of the cowl is not impeded since the cord 42 is axially arranged and since the ball bearing minimizes the friction caused by the pull. Upon releasing the cord 42, the louvers close by their own weight.

Having thus described my invention, what I claim is:

1. A ventilator comprising in combination a rotatably mounted cowl, said cowl having a laterally opening window and a wind vane adapted to turn said window in the direction to which the wind blows, louvers in said window, a bar pivoted to the cowl at a point opposite said louvers and operatively connected to said louvers, and means connected to said bar at the axis of the cowl, whereby the bar can be moved to operate said louvers.
2. A ventilator comprising in combination a stationary part adapted to be attached to a roof, a tubular support extending vertically upward from the center of said stationary part, a cowl pivoted on said support, means carried by said cowl for regulating the draft therethrough, a sleeve slidably mounted upon said support, a flexible member depending through said support and attached to said sleeve, and connections between said sleeve and said louvers whereby a longitudinal movement of said sleeve upon said support shall operate said regulating means.
3. A ventilator comprising in combination a stationary part adapted to be attached to a roof, a tubular support extending vertically upward from the center of

said stationary part, a cowl pivoted on said support, means carried by said cowl for regulating the draft therethrough, a bar pivoted at one side of the cowl and extending diametrically thereacross, a sleeve slidably and rotatably mounted on said support and pivoted to said bar, the free end of said bar being connected to said regulating means, and a cord or chain depending through said support and associated with said sleeve, and adapted to slide the same to move said bar to operate said regulating means.

4. A ventilator comprising in combination a stationary part adapted to be attached to a roof, a tubular support extending vertically upward from the center of said stationary part, a cowl pivoted on said support, means carried by said cowl for regulating the draft therethrough, a bar pivoted at one side of the cowl and extending diametrically thereacross, a sleeve slidably and rotatably mounted on said support and pivoted to said bar, the free end of said bar being connected to said regulating means, a second sleeve slidably mounted on said support and swiveled to said first mentioned sleeve, and a cord or chain depending through said support and connected to said second mentioned sleeve.

5. A ventilator comprising in combination a stationary part adapted to be attached to a roof, a tubular support extending vertically upward from the center of said stationary part, a cowl pivoted on said support, said cowl having a laterally opening window and a wind vane adapted to turn said window in the direction to which the wind blows, louvers in said window, a sleeve slidably mounted upon said support, a flexible member depending through said support and attached to said sleeve, and connections between said sleeve and said louvers whereby a longitudinal movement of said sleeve upon said support shall operate said louvers.

6. A ventilator comprising in combination a stationary part adapted to be attached to a roof, a tubular support extending vertically upward from the center of said stationary part, a cowl pivoted on said support, said cowl having a laterally opening window and a wind vane adapted to turn said window in the direction to which the wind blows, louvers in said window, a bar pivoted at one side of the cowl and extending thereacross, a sleeve slidably and rotatably mounted on said support and pivoted to said bar, the free end of said bar being connected to said louvers, and a cord or chain depending through said support and associated with said sleeve and adapted to slide the same.

7. A ventilator comprising in combination a stationary part adapted to be at-

tached to a roof, a tubular support extending vertically upward from the center of said stationary part, a cowl pivoted on said support, said cowl having a laterally opening window and a wind vane adapted to turn said window in the direction to which the wind blows, louvers in said window, a bar pivoted at one side of the cowl and extending thereacross, a sleeve slidably and 10 rotatably mounted on said support and pivoted to said bar, the free end of said bar being connected to said louvers, a second sleeve slidably mounted on said support and swiveled to said first mentioned sleeve, 15 and a cord or chain depending through said support and connected to said second mentioned sleeve.

8. A ventilator comprising, in combination, a stationary part adapted to be attached to a roof, a tubular supporting member extending vertically upward from the

center of said stationary part, a cowl having a laterally opening window and a wind vane adjacent to said window, means within the window for regulating the draft therethrough supporting members within 25 said cowl, a bearing secured to said supporting members and resting upon said first named supporting member, reciprocable operating means located in said tubular support, connections between said operating means and said draft regulating means whereby the latter may be controlled, and means secured to the side of said cowl and engaging said tubular member whereby 30 35 swaying of said cowl may be prevented.

In testimony whereof, I hereunto affix my signature in the presence of two witnesses.

ANTON JOCH.
